UNITED STATES PATENT OFFICE.

ALBERT ALANSON MORTON, OF WALLA WALLA, WASHINGTON.

CURRENT-MOTOR.

No. 802,228.

Specification of Letters Patent.

Patented Oct. 17, 1905.

Application filed January 27, 1905. Serial No. 242,859.

To all whom it may concern:

Be it known that I, ALBERT ALANSON MORTON, a citizen of the United States, and a resident of Walla Walla, in the county of Walla 5 Walla and State of Washington, have invented a new and Improved Current-Motor, of which the following is a full, clear, and exact description.

This invention relates to improvements in 10 motors operated by stream-currents; the object being to provide a motor of this character that will be simple in construction, having no parts liable to get out of order, and that will be operated by currents of any force and 15 regulated as to the throw of its transmission-rod leading to machinery on shore.

I will describe a current-motor embodying my invention and then point out the novel features in the appended claims.

20 Reference is to be had to the accompanying drawings, forming a part of this specification, in which similar characters of reference indicate corresponding parts in all the figures.

Figure 1 is a side elevation of a current- 25 motor embodying my invention. Fig. 2 is a section on the line 2 2 of Fig. 1. Fig. 3 is a bottom plan, and Fig. 4 is a detail showing a portion of the power-shaft and the bearing-sleeve for the paddle-rod.

30 The frame of the motor comprises beams 5, extended outward from any suitable anchorage--such, for instance, as from the shore of the stream or from an anchored float or the like--and suspended from the beams 5 by 35 means of rods 6 is a platform 7. A power-shaft 8 has its upper bearings in a boxing 9, attached to a platform 10, secured to the upper sides of the beams 5, and its lower bearing in a boxing 11, mounted on the platform 40 7, through which the said shaft extends. On the upper end of the shaft 8 is a crank 12, with which the transmission-rod 13 has a universal-joint connection 14. Secured to the lower end of the shaft 8 and below the platform 45 7 is a sleeve 15, which extends horizontally, and mounted to rotate in this sleeve is a rod 16, carrying paddles 17 18 at opposite sides of the power-shaft. These paddles 17 and 18 are arranged at right angles to each 50 other, so that when one is in vertical position to be acted upon by the current the other will be in horizontal position above the water-surface. It may be here stated that the paddles do not travel a continuous circle, but 55 move back and forth through an area of about

one-quarter of a circle. In other words, the paddles operate with reciprocating motion.

An arm 19 is mounted to swing on the shaft 8, as here shown, below the platform 7 and extends outward over an arc-shaped plate 60 20, provided at opposite sides of its center with perforations for receiving stop-pins 21. By limiting the movement of the arm 19 so as to regulate the speed of the transmission-rod--that is, by placing the pins 21 closer together--the speed will be increased and will be lessened when the pins are placed farther apart. Extended outward in opposite directions from the inner end of the arm 19 are locking-rods 22. These locking-rods pass 65 70 loosely through perforations in arms 23, secured to the sleeve 15, and are designed to be engaged by oppositely-extended stop-arms 24 on the rod 16.

In the operation, referring to Fig. 3, the 75 current-pressure is on the paddle 18, and the locking-rod 22 is engaged by the arm 24 adjacent to the paddle 17, holding said paddle 17 in horizontal position. As the paddle 18 reaches the point *x* the arm 19 will come in 80 contact with the pin 21, as indicated by dotted lines in Fig. 3, and then by a continued movement of the paddle, the arm 19 remaining still, will draw the locking-rod 22 inward, releasing the arm 24 adjacent to the paddle 17 85 and force the other rod 22 outward to be engaged by an arm 24 adjacent to the paddle 18. The current will then immediately reverse the paddles, so that the paddle 18 will be in a horizontal position and the paddle 17 90 in a vertical position, as indicated by dotted lines *y* in Fig. 3, so that the water-current will reverse the motion.

Having thus described my invention, I claim as new and desire to secure by Letters Patent— 95

1. A current-motor comprising a vertical shaft, a horizontal rod at the lower end of the shaft, paddles on said rod at opposite sides of the shaft arranged at right angles to each other, and means for automatically causing a 100 reversing of the paddles and the motor upon the partial rotary movement of the shaft.

2. A current-motor having reciprocating rotary movement comprising a frame, a vertical power-shaft supported by the frame, a 105 horizontally-disposed sleeve on the lower end of said shaft, a rod mounted to turn in the sleeve, paddles on said rod on opposite sides of the shaft and at right angles to each other, automatically-actuated means for locking the 110

rod to hold the paddles alternately in vertical and horizontal position and means for regulating the reciprocating movements of the motor.

- 5 3. A current-motor comprising a frame, a vertical power-shaft, a horizontally-disposed sleeve in the lower end of said shaft, a rod mounted to turn in said sleeve, paddles on said rod at opposite sides of the shaft, and 10 arranged at right angles to each other, an arm having swinging connection with the shaft, means controlled by said arm for locking the paddles in position, and means for limiting the movement of the arm.
- 15 4. A current-motor comprising a frame, a power-shaft supported by the frame, a sleeve arranged at right angles on the lower end of the shaft, a rod extended through said sleeve and mounted to rotate, paddles on said rod at 20 right angles to each other, arms extended from the rod at opposite ends of the sleeve, an arm loosely mounted on the shaft and extended outward therefrom, guide-lugs on the ends of the sleeve, locking - rods extended 25 from said last-named arm through said guide-lugs, and adapted to engage the arms on the

paddle-carrying rod, and means for limiting the movement of said last-named arm.

5. A current-motor comprising a frame, a vertical power - shaft supported thereby, a 30 horizontally-disposed sleeve on the lower end of said shaft, a rod mounted to rotate in said sleeve, paddles carried by said rod at right angles to each other, guide-lugs on the ends of the sleeve, oppositely - extended arms on 35 the rod at opposite ends of the sleeve, an arm mounted to swing on the power-shaft, rods extended in opposite directions from said arm and through the guides and adapted for engagement with the arm carried by the rod, a 40 segment-plate along which the outer end of the arm on the power-shaft moves, the said plate having a series of perforations at each side of its center, and stop-pins for engaging in the perforations.

45 In testimony whereof I have signed my name to this specification in the presence of two subscribing witnesses.

ALBERT ALANSON MORTON. [L. S.]
